UNITED STATES PATENT OFFICE

2,042,270

TOY PARACHUTE DEVICE

Fred V. Moore and Albin B. Johnson, Harvey, Ill.,
assignors of one-half to Neil A. Kingston

Application June 23, 1933, Serial No. 677,211

10 Claims.

(Cl. 46—86)

This invention relates to a toy parachute device and more particularly to a toy miniature person or doll equipped with a toy parachute device in order to enable the said device to be thrown up in the air, and means for bringing the parachute into effective operation at or near the maximum ascending height of the device, and its consequent functioning as hereinafter described.

10 A further important object of our invention is to produce a toy equipped with a parachute that is a practical device rather than one which on paper looks like it should work or be operative, but which in practice and actual tests is absolutely worthless. To this end we have made dozens of samples and hundreds of tests or trial flights, until we conceived and perfected the invention herein disclosed, described and claimed, and which tests were thoroughly practical and highly successful. On the other hand we have tested out other devices which theoretically function in a substantially different manner, by substantially different means, and which have been presented to the public heretofore, but have been found entirely inoperative and impractical.

25 One other important object of our invention is to provide a practical device that is very inexpensive as to the cost of manufacturing the same. Since these devices will appeal mostly to children 30 the cost must be kept down in order not to restrain the sales demand. Similarly a further object is to have the device so mechanically simple and free from intricacies so as to eliminate, or at least obviate, the undesirability of frustrating the mechanism by jarring, breaking or otherwise destroying the operability of the said device. This latter is the actual situation with some of the devices of this character which have been called to our attention.

40 This and other objects will appear by an inspection of the drawing, to which like reference characters are applied to like parts in the several views shown, and in which

Fig. 1 is an elevational perspective view showing the device at an angle so as to present the rear and the left front side of the device, with the parachute inserted within the hollow portion of the doll or body;

Fig. 2 is a perspective view showing the device as it appears descending with the parachute in operative position;

Fig. 3 is a cross-sectional view taken on the lines 3—3 of Fig. 1 looking in the direction of the arrows;

55 Fig. 4 is a side elevational view showing a modi-

fied form of holding the casing in closed position; and

Fig. 5 is similarly an elevational view showing a further modified form of holding the casing in operative position.

In the figures 1 represents the doll or man as a whole, 2 the head thereof, 3 the casing attached to the doll by means of the hinge 4, which hinge is secured to the doll by means of the plate 5 held in place by the screws 6; 7 represents the 10 openings in the sides of the casing and 8 represents flanges or protruding portions of the casing against which the cords 9 press when the casing is in closed position, and 10 represents the eyelet or opening in the bottom part of the doll through which the cords 9 pass. 11 represents the 15 hole or opening in the back of the casing through which the strings 12 of the parachute extend. 13 is the top of the parachute, 14 represents a metal plate attached to the casing 3 20 by means of the screw 15, said plate having a flange 16 at the bottom thereof. 17 represents an L shaped hook adapted to contact with the member 16, said hook having an eyelet 18, to which eyelet is attached an elastic band 19, said 25 elastic band attached at 20 to a cord 21, said cord having a knot 22 therein sufficiently large so as not to permit it to pass through the eyelet 10. 23 represents a bracket protruding from the 30 thigh portion of the doll, a lever 25 is pivoted at 24 on said bracket and having a right-angled section protruding upward at 26, and the other end of said lever being attached at 27 to a cord 28.

The operation of our device is quite simple, and in its simplicity and inexpensiveness resides 35 its great commercial appeal.

Referring for the present to Figs. 1, 2 and 3, the parachute is rolled and inserted within the casing and the casing is in closed position, as shown at Fig. 1. The person wishing to manipulate the toy grabs the cords 9 at a convenient extremity exterior of the eyelet 10, and whirls the same around several times, thus causing the cords 9 to become tense, which tends to hold the casing in closed position, partly because of the 40 location of the holes 7, partly because of the protruding portions 8 and partly because the cords 9 are brought towards the front of the doll, thereby causing the relative position of the cords to hold the casing in closed position.

We have found in actual test that it is preferable, but not indispensable, to weight the head 45 2 of the doll, so that when the device is hurled upwardly, after swinging the same around a time or two, the device will proceed upwardly in the 50 55

air head first, and the pressure of gravity will tend to keep the casing closed on the upper flight of the device. When the device reaches about its maximum height, or possibly a trifle later, the releasing of the tension of the cords 9, plus the resistance of the air, will cause the casing to open as shown in Fig. 2 and permit the parachute to be released, whereupon the device floats gracefully and safely to the earth.

10. Fig. 4 shows a modified form of our device in that the knot 22 is placed at such a point that when the casing 3 is held in closed position by means of the hook 17 and the flange 16 the elastic 19 is under tension. As the device is hurled upwardly the casing is held in place by reason of the pressure of gravity, but the hook 17 is released from the L 16 by reason of the contraction of the elastic 19.

20. In Fig. 5 the pressure of the cord 9, which is in that figure an extension of the cord 28, holds the casing in place while the device is being whirled. The lever 25 in the position shown in Fig. 5 is fulcrumed at 24; when pressure cords 28 and 9 are released gravity forces the lever down and thus permits the casing to open.

25. Having thus described our invention, what we claim and desire to protect by Letters Patent is:

1. In a device of the character described comprising a hollow body portion, a casing hingedly connected with said body portion, said casing having extending therefrom a plurality of cords extending downwardly of said body portion and passing through an eye or opening in the lower extremity of said body portion, said cords serving as means for hurling the device upwardly and holding the casing closed, a parachute secured to the device and held within the body portion and the casing and adapted to unfold to support the body portion when the latter opens.

2. In a device of the character described comprising a hollow body portion, a casing hingedly connected with said body portion, said casing having extending therefrom a plurality of cords extending downwardly of said body portion and passing through an eye or opening in the lower extremity of said body portion, said cords serving as means for hurling the device upwardly and holding the casing closed, said casing having flanges or raised portions against which said plurality of cords under tension tend to exert pressure, a parachute secured to the device and held within the body portion and the casing, and adapted to unfold to support the body portion when the latter opens.

3. In a device of the character described comprising a hollow body portion, a parachute held within the body portion and adapted to unfold to support the body portion when the body portion opens, said parachute being held in its place within the hollow body by means of cords as the device is hurled upwardly and thereafter being held in place in its upward flight by means of gravity exerting itself against the hollow body portion, said cords also serving as means for hurling the device upwardly.

4. In a device of the character described comprising a hollow body portion, a parachute held within the body portion and adapted to be released at or near the maximum height of the device on being thrown upwardly, a single means 5 for the dual purpose of hurling said device upwardly and securing the parachute in a collapsed condition prior to its release.

5. In combination with a toy projectile, a parachute adapted to be released and opened up at or 10 near the maximum height to which said projectile is hurled, means by which flight of the projectile is effected, and said means preventing the said parachute from prematurely escaping from said projectile. 15

6. In a device of the character described comprising a hollow body portion, a cover for closing said hollow body portion, a parachute held within the body portion and adapted to unfold to support the device when the cover opens and 20 the device floats to the earth, said parachute being held in its place within the hollow body portion while the device is being hurled by the tension of a cord which is employed for hurling the device upwardly. 25

7. In a device of the character described comprising a hollow body portion, a casing hingedly connected with said body portion, said casing having extending therefrom a cord downwardly of said body portion and passing through an eye 30 or opening in the lower extremity of said body portion, said cord serving as a means for hurling the device upwardly and holding the casing closed, a parachute secured to the device and held within the body portion and the casing and 35 adapted to unfold to support the body portion when the latter opens.

8. In a device of the character described, comprising a hollow body portion, a casing hingedly connected with said body portion, said casing 40 having a cord extending downwardly of said body portion and passing through an eye or opening in the lower extremity of said body portion, said cord serving as a means for hurling the device upwardly and holding the casing 45 closed, said casing having flanges or raised portions against which said cord under tension tends to exert pressure, a parachute secured to the device and held within the body portion and the casing and adapted to unfold to support the 50 body portion when the latter opens.

9. In a parachute toy a body portion, a parachute associated with said body portion in a collapsed condition, and means for hurling the toy in the air, said means also functioning to retain 55 the parachute collapsed only while the toy is being hurled by the operator.

10. In a parachute toy a body portion, a parachute associated with said body portion in a collapsed condition and a cord attached to the body 60 for hurling the toy in the air, said cord also functioning to retain the parachute collapsed while being hurled by the operator and thereafter releasing its retention of the parachute.
